UNITED STATES PATENT OFFICE.

WALTER I. LEGGETT, OF GALESBURG, ILLINOIS.

DESIGN FOR A SCRAPER FOR KITCHEN UTENSILS.

SPECIFICATION forming part of Design No. 23,068, dated February 13, 1894.

Application filed December 21, 1893. Serial No. 494,354. Term of patent 14 years.

To all whom it may concern:

Be it known that I, WALTER I. LEGGETT, a citizen of the United States, residing at Galesburg, in the county of Knox and State of Illinois, have invented and produced a new and original Design for a Scraper for Kitchen Utensils; and I do hereby declare the following to be a full, clear, and exact description of the same, reference being had to the accompanying drawing, forming a part thereof.

The figure is a perspective view of a scraper for kitchen utensils generally, illustrating my design. The leading feature of my design consists in an open tubular figure or body with a blade falling from one edge, and the opposite edge terminating angularly within the tube or cylinder.

A, indicates the tube or cylinder; and B, the blade. The tube or cylinder which is represented as formed on one end of the blade, is

disposed longitudinally of the latter, and the blade which is a continuation of the cylinder, is of a broad and flat contour, having a circular opening a, through it near one of the lateral edges and adjacent to the tube or cylindrical portion, and with one round and one angular corner.

The whole article is represented as formed from a single sheet of material with the blade falling from one edge of the tube or cylinder.

What I claim is—

The design for a scraper for kitchen utensils, substantially as shown and described.

In testimony whereof I affix my signature in presence of two witnesses.

WALTER I. LEGGETT.

Witnesses:

E. S. SCOTT,
CORA JOHNSON.
